GAS BURNER SYSTEM UTILIZING SAFETY
PUSH BUTTONWilliam A. Ray, North Hollywood, Calif., assignor
to General Controls Co., a corporation of California

Application July 12, 1948, Serial No. 38,342

11 Claims. (Cl. 158—131)

1

This invention relates to a gas burner system, such as shown for example in application Serial Number 746,409, filed on May 6, 1947, and now Patent No. 2,520,961, in the name of William A. Ray, for Safety Push Button Gas Burner Control System. This application is a continuation in part of said application.

In the said prior application, there is described a system in which the pilot burner must be ignited and burning before the main burner can be ignited; and the arrangement is such that upon pilot flame failure, the main burner valve is closed and the supply of gas to the pilot burner is also interrupted. To initiate the operation of the system or reset the mechanism, the igniter is energized and a temporary by-pass for supplying fuel to the burner is provided. As soon as the pilot burner is ignited, the resetting device is released, and after a short time delay, the main burner valve is permitted to open.

It is one of the objects of this invention to provide an improved system of this character.

It is another object of this invention to ensure that the igniter cannot be energized until after a time delay has occurred upon interruption of the operation. It is thus assured that re-ignition immediately upon pilot flame failure cannot occur. Thereby danger of explosion of unignited fuel left at the burner is avoided, since there is ample time for the escape of the fuel.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a diagram of a system incorporating the invention;

Fig. 2 is a sectional view of the apparatus utilized in the invention, and shown in the inactive position in which both the pilot burner and the main burner are unlighted;

Fig. 3 is a view similar to Fig. 2, but illustrating the position of the apparatus when the main burner is conditioned for use;

Fig. 4 is a fragmentary view similar to Fig. 2, and illustrating the manner in which the operation of the system may be initiated; and

2

Fig. 5 is an enlarged sectional view, taken along a plane corresponding to line 5—5 of Fig. 2.

In Fig. 1 a main burner 1 is shown as supplied from a fuel gas conduit 2. Controlling the flow of fuel to the burner 1 is an electromagnetically operated valve 3. A pilot burner 4 is supplied with fuel from the conduit 2 through the conduits 5 and 6. Interposed between these conduits is a control apparatus 7 which incorporates valve means for controlling the passage of fuel to the pilot burner.

The pilot burner 4 may be ignited through an electrically energized igniter 8. This igniter 8 may be of the spark gap type, and may be supplied with electrical energy through a transformer 9. The secondary winding 10 of the transformer 9 is directly connected to the igniter 8. A ground connection 11 may be provided for one terminal of the winding 10 as well as for the conduit 5. Power is supplied to the primary winding 12 of the transformer 9 from a step-down transformer 13 appropriately connected to a commercial source of electrical energy.

The control device 7 is so arranged that it will condition the valve 3 so that it may be opened only in the event that the pilot flame 14 is in existence. When the pilot flame 14 is extinguished, the valve 3 is maintained closed, and the supply of fuel to the burner 1 is interrupted.

For this purpose, in the present instance use 30 is made of a thermocouple 15 having a hot junction arranged to be heated by the pilot flame 14. When the pilot flame 14 is in existence, the thermocouple 15 energizes a delicate relay 16. This relay, when it is energized, conditions the 35 valve 3 so that it may be opened whenever more heat is required.

As shown in Fig. 1, a thermostat 17 is inserted in the circuit of the electromagnetically operated valve 3. This thermostat may be disposed in the 40 room or space that is to be heated by the aid of the burner 1. When the thermostat closes a contact, due to a lowered temperature, the main valve 3 is opened, and the burner 1 is ignited by the pilot flame 14.

The control device 7 includes a main body 18 which may be a casting. This main body has an inlet 19 and an outlet 20 connected respectively to the conduits 6 and 5. This structure is shown most clearly in Figs. 2, 3, and 4.

The lower surface 21 of body 18 forms one wall of a pressure chamber 22. A movable wall for the chamber is formed by a flexible diaphragm 23. This diaphragm 23 is used for performing controlling functions as hereinafter described.

The outer edge of diaphragm 23 is held in place

against the lower flange on the body 18 by the aid of a cover member 25 that is appropriately attached to the body 18.

The diaphragm 23 is provided with a large disc 24 engaging its lower surface. Above the diaphragm 23 is another smaller disc 26. These two discs are held tightly against the diaphragm 23 by the aid of a stem member 27. The head 28 of the stem member engages the disc 26. A nut 29, threaded on the stem member 27, holds the assembly together.

The stem member 27 is slidably mounted in a bushing 30 that is firmly supported in the cover 26. A compression spring 31 is interposed between the disc 24 and the cover member 25 to urge the diaphragm 23 to the upper position illustrated in Fig. 2. This spring is quite light, and is sufficient to move the diaphragm in this manner when there is no fluid pressure exerted in chamber 22.

A chamber 32 is provided in the body member 18 and communicating with the inlet 19. This chamber is closed at its lower end by a sealing wall 33 appropriately attached to the body 18. This space 32 is sealed, as by the cover 34 that encloses the relay 16.

The relay 16 has a core 35, the lower leg of which is supported on a frame 36. This frame 36 has an opening 37, and is appropriately supported upon the upper surface of the body 18, screws 38 being shown for holding the core 35 to the frame 36.

The upper leg of the core 35 supports the coil 39 which is energized by the aid of the thermocouple 15. A circular pole piece 40 is carried by the upper leg of the core 35. When the coil 39 is energized, it attracts a light armature 41 to the position indicated in Fig. 3. This armature 41 passes through opening 37, and is supported for tilting on the upper edge of the frame 36. It is urged against the knife-edge 42 provided at the left-hand end of the lower leg of the core 35. A light compression spring 43 has its right-hand end abutting the armature 41 below the knife edge 42. The left-hand end of the spring 43 is clamped between the frame 36 and the body 18. This spring 43 is sufficient to urge the armature 41 to the position shown in Fig. 2 when the relay coil 39 is unenergized.

The lower portion of the armature 41 in this position serves to close a jet opening 44 in a jet member 45. This jet member 45 controls the passage of fuel to the conduit 5. When it is closed by the armature 41, gas cannot flow through the jet from chamber 32 to conduit 5. However, when coil 39 is energized, the jet is opened, as shown in Fig. 3, and fuel can flow through the jet member 45 to the outlet 20 and conduit 5.

The jet member 45 is appropriately supported in the body 18 by being threaded therein. A packing gland is provided for the jet member 45, as by the packing 46 and the gland nut 47.

In the position shown in Fig. 1, no fuel can pass to the pilot burner 4. In order to initiate operation of the system by lighting the pilot burner 4, a bypass is provided around the jet member 45 to supply gas to this burner. For this purpose a passageway 48 is provided in the body 18, and which intersects the passage 49 interposed between the jet member 45 and the outlet 20. The upper end of this passage 48 may be placed in communication with the chamber 32 when a valve member 50 is raised. This valve member 50 has a tapered portion that seats on the upper

edge of the passageway 48. It is provided with a stem 51 which is guided in the boss 52 formed on the body 18. A compression spring 53 urges the valve member 50 to closed position. For this purpose its upper end engages the body 18 and its lower end engages a spring-retaining washer 54 attached to the end of the stem 51.

When it is desired to initiate operation of the system, the stem 51 is raised, thereby causing fuel to pass to the pilot burner 4. The path of the fuel is formed by inlet 19, chamber 32, passageways 48, 49 and 20, and conduit 5.

Simultaneously with the raising of the stem 51, the igniter 8 is energized. For this purpose use is made of a circuit controller including a resilient arm 55. This resilient arm 55 is attached at its left-hand end to a bracket 59 depending from the cover member 25. The arm 55 carries at its right-hand end a support 58 to which are attached the upper contact member 56 and the lower contact member 57. These contact members are electrically connected, but are insulated from the support 58. A connection may be made in any appropriate manner to the contacts 56 and 57.

The upper contact 56 is adapted to cooperate with a stationary contact 60, formed by a headless screw. This contact 60 is threaded into a bracket 61 (see Fig. 5) that is insulated from and supported on the cover member 25.

Similarly, the lower contact 57 is adapted to cooperate with a stationary contact screw 62, similarly supported on an insulated bracket 63. In the neutral or inactive position of the arm 55, none of the contacts is in engagement.

Arm 55 extends between the stem 21 and a push button plunger 64. This push button plunger has a collar 65 that seats on the upper surface of a guide bushing 66. This guide bushing 66 is appropriately supported in a supplemental cover member 67 supported below the cover 25 and enclosing the circuit controlling mechanism.

The push button stem 68 extends below collar 65 and has a threaded end carrying a push button 69. A compression spring 70, interposed between the button 69 and the upper wall of the bushing 66, serves to urge the push button stem 68 to the inactive position shown in Fig. 2.

When it is desired to initiate operation of the system, the push button 69 is pushed inwardly, as illustrated in Fig. 4. The arm 55 is flexed upwardly against the stem 21, and this stem is thereafter moved upwardly. The head 28 of the stem in turn contacts the stem 51 and valve 50 is raised. Accordingly, fuel can flow to the pilot burner 4.

At the same time contact 56 is urged into engagement with contact 60. The circuit is established for the igniter from transformer 13, connection 71, contacts 56 and 60, connection 72, primary winding 12, and connection 73, to the transformer 13.

Shortly after the pilot burner 4 is ignited, the thermocouple 15 energizes coil 39 and the jet 44 is uncovered, as shown in Fig. 3. Fuel can then pass from chamber 32 directly to the jet 44 and thence to the pilot burner. It is then no longer necessary to keep the push button 69 depressed, and it may be released, causing opening of the igniter contacts 56, 60.

Fuel pressure can also enter chamber 22 to urge the diaphragm 23 to its lowered position of Fig. 3. This is accomplished by the passage of fuel from passageway 20 through an orifice 74

formed in a hollow screw 75. The orifice 74 is made quite restricted so that an appreciable time occurs before the diaphragm 23 assumes the position of Fig. 3. In this position contacts 57 and 62 are brought into engagement. These contacts condition the electromagnetic valve 3 so that it may be opened as required by the thermostat 17.

The circuit for the electromagnetic valve can be traced from the transformer 13, lead 71, contacts 57 and 62, thermostat 17, valve 3, and connection 73. The valve 3 is now under the control of the thermostat 17. The active position of the apparatus is illustrated in Fig. 3.

Should the pilot flame 14 fail for any reason, the relay 16 is deenergized and the jet 44 is covered by the armature 41. In that event there is an interruption in the flow of fuel to the pilot burner 4. At the same time pressure from chamber 22 is gradually released through the orifice 74 and the pilot burner 4. The system then gradually returns to the inactive position of Fig. 2.

The engagement between contacts 57 and 62 may be broken with a snap action whenever stem 27 releases arm 55 from the position of Fig. 3. For this purpose use is made of a small, permanent magnet 76 of horse-shoe shape, shown most clearly in Fig. 5. This permanent magnet 76 is attached to the supporting member 58, as by the aid of a screw 84.

The poles of this permanent magnet are in engagement with the magnetic member 77. This member 77 is appropriately supported on the cover member 25.

In the event of pilot flame failure, it is essential to prevent energization of igniter 8 for a short period, to permit accumulated unignited fuel adjacent the burner to escape. Otherwise an explosion might occur. Provisions are therefore made to prevent actuation of the push button 69 until all of the fuel has been allowed to escape.

Thus, a pivoted lock 78 is provided, mounted upon a stationary pin 79. This pin is appropriately supported on any convenient stationary part of the apparatus. The lower end of this lock 78 is bifurcated to permit it to pass to the locking position of Fig. 3 around the push button stem 64. In this locking position of Fig. 3, the push button 69 is stopped by engagement of the collar 65 with the lock. This engagement is substantially in alignment with a vertical line through the center of pin 79; thus the lock 78 serves effectively as a strut, preventing actuation of the push button 69.

The locking position is effected by the aid of a member 80 formed integrally with the support 58. This member 80 engages the upper edge of the lock 78, swinging it to the locking position when the arm 55 is urged downwardly by the stem 27. When the arm 55 is released, the lock 78 is also released to the position shown in Figs. 2 and 4, permitting the collar 65 to pass the lock. Appropriate means, such as a light spring 81, may be used to urge the lock 78 to the releasing position.

By this arrangement it is ensured that the space 22 above diaphragm 23 must be vented before the igniter 8 can be energized. Accordingly, there is no danger that unignited fuel will be inadvertently exploded in the furnace chamber. A time delay thus necessarily occurs upon a flame failure, before the system can again be placed into operation.

The inventor claims:

1. In a gas burner control system: a main

burner; a pilot burner; an igniter for the pilot burner; a valve for controlling the passage of fuel to the main burner; means responsive to the existence of a flame at the pilot burner for conditioning said valve so that said valve may be opened; means, including a movable member, for energizing the igniter; a releasable lock for holding the member against operation; and means for maintaining the lock in locking position while the pilot flame is in existence.

2. In a gas burner control system: a main burner; a pilot burner; an igniter for the pilot burner; a valve for controlling the passage of fuel to the main burner; means responsive to the existence of a flame at the pilot burner for conditioning said valve so that said valve may be opened; means, including a movable member, for energizing the igniter; a releasable lock for holding the member against operation; and means for releasing the lock only when a time delay occurs after the valve closes due to pilot flame failure.

3. In a gas burner control system: a main burner; a pilot burner; an igniter for the pilot burner; a valve for controlling the passage of fuel to the main burner; means responsive to the existence of a pilot flame for conditioning said valve so that the valve may be opened, and including a control device moved to valve conditioning position when the pilot flame is in existence, as well as means urging said control device toward inactive position upon pilot flame failure; means, including a movable member for energizing the igniter and for moving the control device away from its valve conditioning position; a releasable lock for holding the member against operation; and means for maintaining the lock in locking position while the pilot flame is in existence.

4. In a gas burner control system: a main burner; a pilot burner; an igniter for the pilot burner; a valve for controlling the passage of fuel to the main burner; means responsive to the existence of a pilot flame for conditioning said valve so that the valve may be opened, and including a control device moved to valve conditioning position when the pilot flame is in existence, as well as means urging said control device toward inactive position upon pilot flame failure; means including a movable member for energizing the igniter and to move the control device away from its valve conditioning position; a releasable lock for holding the member against operation; and means for releasing the lock only when a time delay occurs after the valve closes due to pilot flame failure.

5. In a gas burner control system: a main burner; a pilot burner; a valve for controlling the passage of fuel to the main burner; an electrically energized igniter for the pilot burner; a circuit controller for alternately energizing the igniter and for conditioning the valve so that the valve may be opened; means responsive to the existence of a pilot flame for moving the circuit controller to valve conditioning position; means manually movable to move the circuit controller to energize the igniter; a releasable lock for holding the manually moveable means against operation, and means for maintaining the lock in active position while the pilot flame is in existence.

6. In a gas burner control system: a main burner; a pilot burner; a valve for controlling the passage of fuel to the main burner; an electrically energized igniter for the pilot burner;

a circuit controller for alternately energizing the igniter and for conditioning the valve so that the valve may be opened; means responsive to the existence of a pilot flame for moving the circuit controller to valve conditioning position; means manually movable to move the circuit controller to energize the igniter; a releasable lock for holding the manually movable means against operation, and means for releasing the lock only when a time delay occurs after the valve closes due to pilot flame failure.

7. In a gas burner control system: a main burner; a pilot burner; a valve for controlling the passage of fuel to the main burner; an electrically energized igniter for the pilot burner; a circuit controller for alternately energizing the igniter and for conditioning the valve so that the valve may be opened; means forming a pressure chamber having a movable wall for urging the circuit controller to valve conditioning position; means responsive to the existence of a pilot flame for supplying fuel under pressure to the chamber, said supplying means including a restricted orifice to delay movement of the wall in either direction, said orifice communicating with a passage to the pilot burner whereby the chamber is exhausted when the pilot flame is extinguished; manually operated means for moving the circuit controller to a position for energizing the igniter; a releasable lock for holding the manually operated means against operation; and means operated by the movable wall when it is in position to condition the valve for maintaining the lock in holding position.

8. In a gas burner control system: a main burner; a pilot burner; a valve for controlling the passage of fuel to the main burner; an electrically energized igniter for the pilot burner; a circuit controller for alternately energizing the igniter and for conditioning the valve so that the valve may be opened; means forming a pressure chamber having a movable wall for urging the circuit controller to valve conditioning position; means responsive to the existence of a pilot flame for supplying fuel under pressure to the chamber, said supplying means including a restricted orifice to delay movement of the wall in either direction, said orifice communicating with a passage to the pilot burner whereby the chamber is exhausted when the pilot flame is extinguished; manually operated means for moving the circuit controller to a position for energizing the igniter; a releasable lock for holding the manually operated means against operation; and means carried by the circuit controller for moving the lock to holding position when the circuit controller is urged to valve conditioning position.

9. In a gas burner control system having a main burner, a valve for the main burner, and

an igniter for the pilot burner: means, including a movable member, for energizing the igniter; a releasable stop adapted to engage said movable member; and movable means positioned according to the existence or non-existence of a pilot flame, said means cooperating with said releasable stop, said means in one position conditioning the main valve so that it may be opened, and also causing the releasable stop to engage said movable member.

10. In combination: a valve including a valve body having an inlet and an outlet opening; means forming a valve seat in the body; an electromagnet; an armature operated by the electromagnet and cooperating with the seat to open and close the valve; means forming a bypass valve between the inlet and outlet openings; means forming a pressure chamber in communication with the outlet opening and including a movable wall; means carried by the wall for opening the by-pass valve; manual means for urging said wall toward by-pass valve opening position; a circuit controller having an arm movable between two positions and urged to one position by the wall in response to outlet pressure in the chamber; and a stop operated by the circuit controller arm for preventing operation of the manual means when the circuit controller arm is in said one of its positions.

11. In combination: a valve including a valve body having an inlet and an outlet opening; means forming a valve seat in the body; an electromagnet; an armature operated by the electromagnet and cooperating with the seat to open and close the valve; means forming a bypass valve between the inlet and outlet openings; means forming a pressure chamber including a movable wall; means forming a restricted passageway between the chamber and the outlet; means carried by the wall for opening the by-pass valve; manual means for urging said wall toward by-pass valve opening position; a circuit controller having an arm movable between two positions and urged to one position by the wall in response to outlet pressure in the chamber; and a stop operated by the circuit controller arm for preventing operation of the manual means when the circuit controller arm is in said one of its positions.
